(74) Attorney, Agent, or Firm — Banner & Witcoff, Ltd.

CLAIM

The ornamental design for a bottle, as shown and described.

DESCRIPTION

FIG. 1 is a top, front, right perspective view of a bottle showing our new design;

FIG. 2 is a front view thereof, where the rear view is mirror image of FIG. 2;

FIG. 3 is a right side view thereof, where the left side view is a mirror image of FIG. 3;

FIG. 4 is a top view thereof; and,

FIG. 5 is a bottom view thereof.

The broken lines depicting the remainder of the bottle show features that form no part of the claimed design.
